UNITED STATES PATENT OFFICE.

JAMES G. CURTIS, OF COLUMBUS, OHIO, ASSIGNOR TO THE E. M. HULSE COMPANY, OF COLUMBUS, OHIO, A CORPORATION OF OHIO.

SOFA OR DAVENPORT BED.

1,001,625.

Specification of Letters Patent. Patented Aug. 29, 1911.

Application filed November 10, 1909. Serial No. 527,140.

To all whom it may concern:

Be it known that I, JAMES G. CURTIS, a citizen of the United States, residing at Columbus, in the county of Franklin and 5 State of Ohio, have invented a certain new and useful Improvement in Sofa or Davenport Beds, of which the following is a specification.

The object of this invention is to provide 10 an improved combined sofa or davenport and bed of simple, strong and economical construction, with parts conveniently "knocked down" and packed or created for shipment and easily and quickly assembled. 15 The invention is embodied in the construction herein shown and described and then particularly pointed out in the claims.

In the accompanying drawing—Figure 1 is an elevation of the left hand end of the 20 structure with the end piece of the main frame removed and showing the parts closed or in davenport or sofa forming position. Fig. 2 is a similar view with the same parts opened to bed-forming position. Fig. 3 is 25 a section longitudinally on the line $\alpha-\alpha$ Fig. 1 but showing both ends of the main frame and with the central portion broken out. Fig. 4 is a plan view of the frame in 30 which the seat and bed are mounted, the seat carrying the bed.

The frame, which is best shown in Fig. 4, is a rectangular structure comprised of the front and rear rails 5 and 6 respectively and 35 two end pieces 4^a the latter deeply notched out at their rear corners, as shown at 4^b, to make room for the rear edge of the seat when that member is raised at its forward edge.

The main end pieces 4^a of the structure 40 are made ornamental as usual and are detachably connected to the intermediate frame shown in Fig. 4 by means of bolts and nuts. Said end pieces 4^a support the structure on the floor as usual.

45 The back 7, in the instance shown, consists of a suitably upholstered frame pivoted to the end pieces 4^a at their upper portions as seen at 7^a or so that its lower edge can be swung rearward from ordinary sofa 50 or davenport position. The seat 8 consists of a suitably upholstered frame hinged at its rear portion between the ends 4^a by hinges 8^a secured to the seat frame and to the uppermost rear corner of the end members 4^a of the rectangular frame so that the

seat frame can be tilted back into the notches 4^b. The seat 8 has secured to its ends near its rear portion rigid arms 9 extending downward from the under side thereof, and pivoted at 10^a to the ends of 60 these is the bed frame 10. The bed-carrying frame 10 is provided with an ordinary folding spring comprising spring frame members 11 and 12 pivoted to short intermediate connecting members 13, the latter 65 being pivotally supported on standards 14 secured to the bed carrying frame.

15 are legs for supporting the outer member 12 when the bed is extended and 16 are links for causing the spring member 70 11 to level horizontally with the members 12 and 13 when the bed is opened.

17 is a mattress for the spring.

18 are catch or prop arms pivoted to the 75 ends of the seat frame and extending forwardly, said arms having notches to engage pins 19 secured to the ends 4^a of the rectangular frame shown in Fig. 4. The catch arms 18 have dogs 18^a automatically operative by moving the seat to release the arms 80 from the pins 19. The function of the arms 18 is to latch and prop the seat in raised position when the bed is to be extended. By pressing the seat when in raised position at the top rearward the latch arms 18 can be 85 released to let the seat down after the bed has been folded up toward and secured to the seat. The said latch arms are of a kind in common use and no claim is made to them 90 by themselves.

20 designates a hook secured to a cross piece 21 at the under side of the seat said hook being designed to engage a headed pin 22 on the spring frame 10 so that the spring head can be raised and lowered with the 95 seat.

The seat and back are connected by links 23 so that when the seat is raised the lower portion of the back is pushed rearward out of position to interfere with the movement 100 of the rear edge of the seat. When the bed is extended or unfolded to bed position it can rest on the front rail 6.

It will be observed that the frame in 105 which the seat and bed are carried braces the davenport ends and that those ends in turn brace the said frame. The seat and bed do not require nice adjustment with reference to the davenport ends. The device can be "knocked down" for shipment by simply 110

removing the davenport ends after which the back can be folded down on the seat reducing the structure, minus the davenport ends, to compact form with all the parts 5 united and ready for erection by application of the davenport ends thereto.

What I claim is:

1. In a combined sofa or davenport and bed, a rectangular frame, a seat hinged at 10 its rear portion thereto to be raised and lowered, said seat carrying a frame containing an extensible bed, means for supporting the seat in raised position independently of the said bed frame, and sofa 15 or davenport ends rigidly connected with the ends of said rectangular frame.

2. In a combined sofa or davenport and bed, a rectangular frame having its upper rear portions notched or cut away, a seat 20 hinged at its rear portion to said ends at their upper corners so as to be raised and lowered said seat carrying a frame containing an extensible bed, means for supporting the seat in raised position independently of 25 its said frame, and sofa or davenport ends rigidly connected with the ends of said rectangular frame.

3. In a combined sofa or davenport and bed, a rectangular frame having its upper 30 rear corners notched or cut away, a seat hinged at its rear portion to said ends so as to be raised and lowered said seat carrying a frame containing an extensible bed,

automatically releasable means for supporting the seat in raised position independently 35 of the bed, and sofa or davenport ends rigidly connected with the ends of said rectangular frame.

4. In a combined sofa or davenport and bed, a rectangular frame, a seat hinged at 40 its rear portion thereto to be raised and lowered, said seat carrying a frame containing an extensible bed, means for supporting the seat in raised position, a back linked to the seat and adapted in the dismounted position 45 of the parts and while linked to the seat to fold against the seat, and sofa or davenport ends rigidly connected with the ends of said rectangular frame.

5. In a combined sofa or davenport and bed, a rectangular frame having its upper rear portions notched or cut away, a seat hinged at its rear portion to said ends so as 50 to be raised and lowered, said seat carrying a frame containing an extensible bed, automatically operative locking and supporting 55 means for sustaining the seat in raised position said locking and supporting means extending forwardly and engaging the frame, and davenport ends rigidly connected with 60 the ends of the rectangular frame.

JAMES G. CURTIS.
